UNITED STATES PATENT OFFICE.

JOHN KRALUND, OF BROOKLYN, NEW YORK, ASSIGNOR TO DOEHLER DIE CASTING COMPANY, OF BROOKLYN, NEW YORK, A CORPORATION OF NEW YORK.

DIE-CASTING APPARATUS.

1,416,476.

Specification of Letters Patent. Patented May 16, 1922.

Application filed May 8, 1920. Serial No. 379,712.

To all whom it may concern:

Be it known that I, JOHN KRALUND, a citizen of the United States, residing in the borough of Brooklyn, in the city of New York, county of Kings, and State of New York, have invented certain new and useful Improvements in Die-Casting Apparatus, of which the following is a specification.

My invention relates to improvements in a die casting machine of the character in which a carrier or ladle device transfers molten metal to a die. Such an apparatus is shown, for example, in my Patent No. 1,299,738, dated April 8, 1919. In mechanism of this character the nozzle of the carrier is inserted into an opening in a plate, which opening forms the gate of the die, one part of which is secured or mounted against the plate. When the carrier is thus positioned the molten metal in the carrier is forced, as by air pressure, through the opening into the die, after which the carrier and plate are separated, as by a movement of the carrier away from the plate, back into the melting pot to take another charge.

In the operation of such machines, sprues or gates often become stuck within the gate opening extending through the plate referred to. When this happens operation of the machine must be stopped until the gate opening referred to has been cleaned out and the consequent loss of time is apt to reduce to a considerable extent the effectiveness of the machine.

By my present invention I provide a simple and effective mechanism for knocking out the sprues from the gate opening when the same become stuck therein, with a minimum loss of time. I attain this result by mounting an arm or lever on the plate through which the gate opening extends, this arm carrying a pin which is so positioned as to enter the gate opening and knock against the end of the sprue therein when the arm is oscillated. The arm may effectively be mounted on a shaft which is mounted on top of the plate, the shaft being oscillated, when necessary, by manual means such as a handle on the end of the shaft. With this arrangement the arm may normally be held out of the way of the moving parts and readily operated, with sufficient force to dislodge a sprue from the gate opening, whenever required.

In order that my invention may be more

clearly understood, attention is hereby directed to the accompanying drawings forming part of this application and embodying one form of my invention. In the drawings Fig. 1 represents a view partly in side elevation and partly in section, of a melting pot, the end plate of the die-carrying frame, and the device for knocking out sprues mounted thereon, and Fig. 2 is a front elevation of the end plate with the knock-out device mounted thereon.

Referring to the drawings the melting pot 1 of the apparatus is adapted to contain molten metal which is heated by suitable heating means within the chamber 2. The end plate 3 constitutes part of the die-carrying frame which may be provided with rods indicated at 4 to which the end plate 3 is secured. The die-carrying frame is positioned, or may be positioned, in close proximity to the melting pot 1 so that the horizontal opening or gate 5 extending through plate 3 will be closely adjacent to the upper edge of the melting pot. A removable bushing 6 is preferably fitted within the opening 5.

In the operation of the casting machine the forward half or portion of the die is mounted against the rear surface of end plate 3 so that the opening 5 will communicate with the interior of the die. A movable carrier or ladle may be mounted within the melting pot 1 and operated, as for example, by mechanism such as that described in my patent referred to, so that the carrier will take a charge of molten metal, and then have its nozzle inserted into the forward end of the bushing 6, after which the charge of molten metal is forced through bushing 6 into the die and the ladle then returned to position to take another charge. The mechanism referred to is not part of my present invention and is therefore not illustrated herein. The above brief description will, however, serve to indicate the mechanism with which my present improvement is adapted to coact.

In the embodiment of my invention illustrated the shaft 7 is mounted horizontally in bearings 8 on the top surface of plate 3 and is provided with the hand crank 9. Arm 10 is secured on shaft 7 to oscillate therewith above the melting pot 1. Arm 10 is provided with a pin 11 which is adapted to enter the forward end of bushing 6 when

- 2
- arm 10 is in its lowermost position to contact against a sprue which may have become stuck within bushing 6. Preferably a bolt 12 is mounted within a screw-threaded opening in arm 10 above bushing 6 so as to form an adjustable stop which will contact against the front surface of plate 3 to limit the amount of movement of pin 11 into the opening 5.
- 10 During the normal operation of the casting machine, the arm 10 may be raised out of the path of the movable carrier device as the same moves between the melting pot and the bushing 6. When, however, a sprue be- 15 comes stuck in the bushing 6 the hand lever 9 is operated to oscillate shaft 7 so as to cause the pin 11 to strike a sharp blow against the sprue in the opening so as to dislodge the same.
- 20 What I claim is:
1. In casting apparatus, the combination of a die carrying frame having an end plate with an opening therethrough adapted to serve as a gate for the die, a lever pivoted 25 to said plate having a pin thereon positioned to knock against a sprue in said opening when said lever is oscillated, an adjustable stop pin mounted on said lever to abut against the face of said plate when said pin

enters said opening, said lever being normally positioned with the pin removed from said opening, and a handle for manually oscillating said lever.

2. In casting apparatus, the combination of a die-carrying frame having an end plate with an opening therethrough, adapted to serve as a gate for the die, a shaft on said plate, a handle for oscillating said shaft, an arm secured to said shaft, and a pin on said arm, positioned to knock against a sprue in 40 said opening, when said handle is operated.

3. In casting apparatus, the combination of a die-carrying frame having an end plate with an opening therethrough, adapted to serve as a gate for the die, a lever pivoted 45 to said plate, having a pin thereon positioned to knock against a sprue in said opening, when said lever is oscillated, and an adjustable stop pin mounted in said lever, to abut against the face of said plate when said 50 pin enters said opening.

This specification signed and witnessed this 4th day of May, 1920.

JOHN KRALUND.
